PAPER FASTENER

Edwin S. Roscoe and Frederick W. Ackerman,
Rochester, N. Y., assignors to Yawman & Erbe
Mfg. Co., Rochester, N. Y., a corporation of
New York

Application January 22, 1934, Serial No. 707,727
Renewed February 28, 1939

5 Claims. (Cl. 24—153)

The present invention relates to paper fasteners of the type comprising a backing member having spaced, projecting, flexible tangs adapted to be inserted through spaced perforations in a file of papers or documents, and a keeper for locking the tangs parallel to the surface of the papers after being thus inserted.

The main feature of the invention resides in a one piece keeper for a paper fastener which is easily applied to the tangs of the fastener and which is securely held thereon until such times as it is desired to detach the keeper, when it is easily removed.

Another feature of the invention resides in 15 a keeper which is applied to the tangs of a paper fastener by a movement solely in the principal plane of a file of papers on the fastener, said keeper having a portion intervening between the tangs and the file of papers held thereby so that 20 the tangs are prevented from mutilating the top sheet of the file.

Still another feature of the invention relates to a fastener having retaining parts on the ends of its tangs to interengage with co-operating 25 parts on a keeper to retain the keeper on the tangs.

A further feature of the invention relates to a keeper for a paper fastener, said keeper having a portion engaging an edge of the file of papers 30 to which the fastener has been applied so that it is retained on the tangs of the fastener.

An additional feature of the invention resides in the provision of a keeper for a paper fastener which requires a minimum amount of material in 35 the making thereof and which is economical to manufacture.

These and other features of the invention will appear from the detailed description and claims when taken with the drawings in which Fig. 1 is 40 a perspective view of a paper fastener of the present invention applied to a file of papers inclined so that its main plane is inclined away from the line of vision; Fig. 2 is a cross-sectional view taken along a line intersecting either of 45 the tangs of the fastener at either end of the keeper of Fig. 1; Fig. 3 is a plan view of a portion of a file of papers with the tangs of the fastener bent over into the plane of the file of papers and illustrating the first step in applying the 50 keeper to the tangs; Fig. 4 is an end view of a modified form of the keeper showing one of the tangs in cross-section and Fig. 5 is a longitudinal section of this keeper taken along the line 5—5 of Fig. 4 indicating the tang partially inserted 55 into the keeper; Fig. 6 illustrates a cross-section- al view of a keeper showing a modified arrangement for retaining the tangs, which section may be taken at any point along the keeper preferably near one end thereof; Fig. 7 is a cross-sectional view of a modified form of keeper having 60 thereon a tang-retaining means in the form of a ridge; Fig. 8 is a cross-sectional view of still a different form of keeper employing a different type of tang-retaining means which is provided on the top member; Fig. 9 illustrates a further 10 modified form of keeper in which the tang-retaining means is a folded-over portion on the underside of the top member; Figs. 10 and 11 are cross-sectional views taken through a fragment of a file of papers and through the keeper 15 showing a modified form of means for retaining a keeper on the file respectively illustrating the keeper during its application to the file and also when it has been finally adjusted to its locked position thereon; Fig. 12 is a fragmentary top 20 view and Fig. 13 is a cross-sectional view taken on the line 13—13 of Fig. 12 showing a portion of a keeper similar to that shown in Fig. 8, except that the keeper has been changed slightly to give greater resilience to the end portions of its 25 top member so that the tang-retaining means can be readily disengaged from the tang; Fig. 14 is another modified form of keeper in which the lip on the bottom member thereof is extended 30 slightly at each end to project beyond the main portions of the keeper and thereby assist in retaining the tangs in the keeper; Fig. 15 is a top view of a keeper showing a similar locking arrangement which differs from that shown in Fig. 14 by providing cut-out portions or recesses in 35 the bottom member so that it is unnecessary to extend the lip portion of the keeper beyond the keeper ends; Figs. 16, 17 and 18 represent respectively a top view, an end view and a side view of a modified form of keeper in which the ends of 40 the upper member of the keeper project downward below the plane of the bottom member to enter the perforations in the upper portion of a file of papers; Fig. 19 is a top view of a modified form of fastener applied to a file of papers, the 45 keeper being omitted; Fig. 20 is a cross-sectional view taken on the line 20—20 of Fig. 19 showing how the end portions of the tang interengage or nest; Fig. 21 is a plan view of a keeper suitable for use with a fastener disclosed in Figs. 19 and 50 20, and Fig. 22 is a cross-sectional view taken at any point along the keeper of Fig. 21; Fig. 23 is a plan view of a different type fastener applied to a file of papers and specifically indicating 55 nibs on the ends of the tangs of the fastener; 55

Fig. 24 is a plan view of a keeper suitable for use with the fastener shown in Fig. 23 provided with openings to receive the nibs on the ends of the fastener's tangs; Fig. 25 is a cross-sectional view taken on the section line 25—25 of Fig. 24 indicating the manner in which the nibs on the tangs of the fastener interengage with the slots in the top member of the keeper; Fig. 26 is a cross-sectional view of a modified form of keeper in which the top member instead of being provided with slots is provided with a struck-up portion to receive the nibs on the tangs; Fig. 27 illustrates a keeper in which the top member or cover portion is cut away in the center to assist in inserting and removing the tangs therefrom; Fig. 28 represents a top view of a keeper embodying the different features shown in Figs. 12, 13, 14, 19, 20 and 21, while Fig. 29 is a cross-sectional view thereof taken on the line 29—29 of Fig. 28; Fig. 30 is a top view of a keeper combining the various features disclosed in Figs. 7, 8, 10, 11, 16, 17, 18 and 27; Fig. 31 is a cross-sectional view taken on the line 31—31 of Fig. 30, Fig. 32 is a cross-section taken on the line 32—32 of Fig. 30 and Fig. 33 is an end view of this keeper.

Referring to the drawings, 5 designates the base of a fastener having the tangs 6 and 7 of resilient material which can be bent at right angles to the base for insertion through perforations such as 8 in a file of papers 9 and which can thereafter be bent parallel to the plane of the topmost sheet of the file where they are held by a detachable keeper designated 10. While the fastener is herein shown as having its tangs and base member made of a single piece, it will be understood that the spaced tangs may be made of separate pieces separately fastened to a backing piece such as a binder or folder. The keeper is commonly made of one piece of sheet metal or like material and comprises a base member 11 with a projecting lip 12 adapted to lie on the topmost sheet of the file. This base member is folded at one edge 13 to provide a top member 14 extending in a plane parallel to the principal plane of the member, but spaced therefrom. The free edge 15 of this top member is flared outwardly away from the base member to facilitate the insertion of the tangs 6 and 7 in the keeper. In the preferred form of the invention, the spacing of the top member 14 and base member 11 is such as to retain tangs 6 and 7 frictionally in superimposed relation in the keeper, when the thickness of the file papers 9 is small or to retain these tangs in alignment as shown in Fig. 1 when the thickness of the file is greater. The width of the bottom member 11 and its lip 12 with respect to the top member is such that the tangs 6 and 7 can be folded onto the lip or the lip can be inserted under these tangs after they have been folded into the plane of the paper as shown in Fig. 3, at any rate the tangs 6 and 7 are separated from the top sheet of the file by the bottom member when the keeper is completely applied to the fastener as illustrated in Fig. 1.

In the form of the invention shown in Figs. 1 and 2, the frictional engagement of the tangs 6 and 7 with the bottom member 11 and the top member 14 is relied upon to hold the keeper on the tangs. This arrangement is usually adequate for this purpose, since the bent tangs can rarely lie freely in the exact center of the space between 11 and 14 but will frictionally engage one or both retaining surfaces. Also the tangs during use become bent or corrugated crosswise due to the repeated folding arising from the repeated re-

moval and application of the keeper to the tangs on the addition of any sheets to the file. However, additional retaining means may be provided for holding the keeper on the tangs as shown in Figs. 4 and 5 wherein a portion 16 of the bottom member 5 at each end of the keeper is depressed away from the top member as shown in Fig. 4. However, the lip portion 12 remains in the position shown in Fig. 2 so that during the application of the keeper to the tangs, the tangs engage the end portions 10 of the lip. Each tang in passing under the top member 14 engages the rounded corner 17 between the lip and the bottom portion and thereafter drops into the depressed portion 16 of the bottom member. When it is desired to remove 15 the keeper from the tangs, they will first engage the corner 17 which will offer considerable resistance to the passage of the tangs from their position under the top member.

In the modified form of the invention shown in 20 Figs. 6, instead of having only the end portions of the bottom member depressed as shown in Figs. 4 and 5, the lip member 12 is raised above the plane of the bottom member 16 either near each 25 end or throughout the length of the keeper, so that a rounded corner 19 at the entrance to the space under the top member 14, tends to resist the removal of the tangs from their position under this member.

This same result may be also achieved in the 30 arrangement shown in Fig. 7 wherein a raised embossing or ridge 20 which may extend throughout the length of the bottom member or which may be of short length at each end of the bottom member, restricts the entrance to the space under 35 the top member 14 and thereby restrains the removal of the keeper from the tangs. Still another arrangement for accomplishing this same result is shown in Fig. 8 wherein the top member 14 adjacent its free edge is provided with a de- 40 pressed rib 21 which is either coextensive with the length of the top member or may extend for a short length at each end of the top member for the purpose of restricting the entrance to the 45 space between the base and the top member of the keeper. This embodiment also illustrates the use of a raised portion 12a at the free edge of lip 12, the purpose of which is to prevent cutting of the top sheet of the file as the keeper is being moved into position along the surface of this sheet. 50

A further arrangement for retaining the tangs in the keeper is disclosed in Fig. 9 wherein the free margin of the top member 14 is folded on itself at its underside adjacent the bottom member 11. The free edge 22 of this folded portion is rather 55 abrupt so that it will engage an edge of each of the tangs, so that it may be necessary to spring the edge of the top member away from the bottom member by inserting a knife or other implement therebetween when it is desired to remove 60 the keeper from the tangs.

The keeper may also be held on the tangs by the arrangement shown in Figs. 10 and 11 wherein the lip 12 is provided with a downturned flange 23. The length of this lip should be such that when 65 the tangs 6 and 7 are in their fastening position under the top member 14, the flange 23 will engage the top edge of the file as shown in Fig. 11. To apply this keeper to the fastener, the tangs are folded down on the lip 12 in the manner previously indicated. Thereafter, the keeper is forced to the right as shown in Fig. 10 until the flange 23 engages the edge of the file of papers as shown in Fig. 11. In the removal of this type of keeper from the file, the flange 23 is raised 70

upward by inserting a thin blade thereunder until it will ride on the surface of the uppermost paper in the file as shown in Fig. 10.

In order to facilitate the insertion of the tangs in the keeper, the end portions 14a of the top member 14, may be made more resilient by cutting away portions of the fold 13 between the top and base members as indicated at 24 (Figs. 12 and 13). Although this arrangement has been particularly applied to the arrangement shown in Fig. 8, it is also applicable to any of the modifications shown in Figs. 6, 7, and 9.

A further arrangement for resisting the withdrawal of the tangs from the keeper is shown in Fig. 14 wherein the lip 12 is provided with extensions 12b projecting beyond the ends of the remainder of the keeper so that in applying the keeper to the fastener, the tangs will first be folded on to the lip 12 and as the keeper is moved parallel to the plane of the papers, the tangs will first engage the ends of the extension 12b. Then as they pass under the top member 14, the springiness of the paper compressed under the keeper will cause the forward lateral edges of the tangs to engage the rounded corners 12c of the extensions, thereby tending to retain the tangs in the keeper.

Instead of providing the projections 12b on the lip 12 as in the last-described arrangement, a recess 11a may be cut into the bottom member 11 at each end thereof (Fig. 15). This arrangement functions in like manner to retain the keeper since the tangs on being inserted under the top member 14 will rest in the recesses 11a with their forward edges engaging the rounded corners of the adjacent lip 12.

A further arrangement for retaining the keeper on the tangs of the fastener, is shown in Figs. 16, 17 and 18 wherein the top member 14 is provided at its ends with lugs 25 which are extended outwardly and downwardly to a position below the plane of the bottom member 11 as shown in Figs. 17 and 18. This arrangement permits the tangs to be inserted readily under the top member 14 and yet allows the lugs at each end of the file to drop down into the perforations 8 in the file of papers. It will be understood that in applying this keeper to the fastener the tangs are folded down on the top surface of the lip 12, and thereafter, the keeper is moved along the surface of the top sheet of the file with the lugs 25 engaging this surface. The tangs will enter the space between the top member 14, the lugs 25 and the ends of the base member until the tangs are under the top member. At this time these lugs will spring into their normal position so that they will engage the perforations 8, and by engaging the edges of the papers at these perforations, will resist the displacement of the keeper from this fastener. In order to increase the resilience of the top member adjacent these lugs, the fold 13 between this member and the base member may be cut away at each end as indicated at 26.

In the foregoing arrangements, the fastener including its tangs has been shown as following the usual construction, but in Figs. 19 to 22 inclusive, a modified fastener and its cooperating keeper have been disclosed. The end portions 6a and 7a of the tangs 6 and 7 are herein provided with lengthwise grooves which are arranged to interengage or nest, as best shown in Fig. 20, when the tangs are bent parallel to the main plane of the file of papers after being inserted through the perforations 8 in the file.

Since the tangs cannot be bent at the grooves,

calculations show that these grooves should be no longer than the shortest practicable bend at the free ends of the tangs in the absence of such grooves. Then the maximum amount of overlap of the ends of the tangs should equal the length of the grooved portion. This construction affords the maximum capacity for papers on the fastener. By way of example, the maximum length of each groove can be about $\frac{1}{2}$ inch, the maximum length of each tang less than 1 $\frac{1}{2}$ inches and the capacity of the fastener for papers less than 1 and $\frac{1}{2}$ inches. The keeper for use with this fastener may be similar to that shown in Figs. 1, 2 and 3, but differs therefrom in that the top member 14 is provided with a groove 27 into which the nesting grooved portions 6a and 7a of the tangs enter to retain these tangs in the keeper.

As an alternative construction of the fastener and keeper illustrated in Figs. 23, 24 and 25, the tangs 6 and 7 may be provided near their ends with raised nibs 6b and 7b which respectively enter slots 28 and 29 in the top member 14 of the keeper. In this construction, the operator's fingers or some hard object is used to press the nibs out of the mentioned slots so that the tangs can be disengaged from the keeper. Instead of providing the slots 28 and 29, two correspondingly arranged grooves or a single continuous groove 30 may be formed in the top member 14 of the keeper. It should be noted that in these modified tang constructions, the tangs cannot overlap.

If desired the top member 14 may be cut away as indicated at 31 in Fig. 27 to facilitate the positioning of the tangs 6 and 7 in superimposed relation under this member. As herein shown the embossed nibs 32 in the bottom member near each end thereof help to retain the tangs in the keeper. This arrangement of the nibs is similar to that indicated in cross-section in Fig. 7.

While the several arrangements previously described may be used in various combinations, one possible combination is shown in Figs. 28 and 29 wherein the tang construction of Fig. 19 is used with a keeper having the tang-retaining elements of Figs. 12, 14 and 21. In Fig. 29 the grooves in the tangs and the keeper are inverted as compared with their construction in Figs. 20, 21 and 22 but it will be understood that this arrangement is optional.

Another possible combination of the numerous constructions is shown in Figs. 30, 31, 32 and 33 wherein the features of Figs. 6, 7, 8, 10, 16 and 27 are combined in one keeper. It will be noted in this modification, that the rib 21 in the margin of the top member 14 extends into the end portions or lugs 25 of this member. This rib in addition to strengthening the lugs 25 and the margin of the top member 14 restricts the entrance to the tang-receiving space, the free edge of the top member flaring upwardly from this rib to guide the tangs to said entrance.

What we claim is:

1. A keeper for use with the base and end tangs of a paper fastener, said keeper being formed of a single piece of sheet material folded lengthwise to form a top member and a base member in spaced relation to each other to receive tangs laterally, said base member having a lip projecting laterally therefrom beyond the free edge of said top member, the end portions of said base member as compared with the plane of said lip being spaced more remotely from the plane of said top member.

2. In combination with a file of papers having spaced perforations adjacent one edge thereof, a keeper for use with a paper fastener comprising a base having spaced flexible tangs insertable through said perforations with the free ends of the tangs folded against the top surface of the file, said keeper being provided with a top member and a base member in spaced relation thereto to define a space for receiving the tangs laterally, 10 said base member having a lip projecting laterally therefrom, said lip having a flange adapted to engage the adjacent edge of said file when said tangs are inserted under said top member.

3. In combination with a file of papers having spaced perforations therein, a keeper for use with a paper fastener comprising a base having spaced flexible tangs insertable through said perforations, said keeper being formed of a single piece of sheet material folded lengthwise to provide a 20 base member and a top member in spaced relation whereby a lateral opening is provided in the keeper for laterally receiving said tangs, said top member at each end thereof being provided with an outwardly and downwardly extending lip adjacent the end of the base member projecting across the plane of said base member to enter perforations in said file and thereby retain said keeper on the tangs.

4. A keeper for use with the base and end tangs 30 of a paper fastener, said keeper being made of a single piece of sheet material formed to provide a base member and a top member in superimposed spaced relation thereby defining a recess with a lateral opening for laterally receiving said tangs and for retaining the same, said base member at each end thereof having portions depressed away from said top member, a substantial portion of the longitudinal free margin of said top mem-

ber being provided with a depressed rib extending parallel to the free edge of said margin and projecting toward said bottom member to restrict said lateral opening and to reinforce said margin, the portion of said margin between the rib and 5 the longitudinal free edge of said margin flaring away from said bottom member to facilitate the guiding of the tangs toward said lateral opening on application of the keeper to said tangs, the end portions of said top member being extended 10 longitudinally beyond said bottom member and being turned downward toward said bottom member to cover the respective bends in said tangs.

5. A keeper for use with the base and end tangs 15 of a paper fastener, said keeper being made of a single piece of sheet material formed to provide a base member and a top member in superimposed spaced relation thereby defining a recess with a lateral opening for laterally receiving said tangs and for retaining the same, the end portions of 20 said top member being extended longitudinally beyond said bottom member to form lugs turned downward toward said bottom member to cover the respective bends in said tangs, a substantial portion of the longitudinal free margin of said 25 top member being provided with a depressed rib extending parallel to the free edge of said margin and projecting toward said bottom member to restrict said lateral opening and to reinforce said margin, the portion of said margin between the 30 rib and the longitudinal free edge of said margin flaring away from said bottom member to facilitate the guiding of the tangs toward said lateral opening on application of the keeper to said tangs, said rib extending into said lugs. 35
